William James Barnes

UNITED STATES PATENT OFFICE.

WILLIAM JAMES BARNES, OF JERSEY CITY, NEW JERSEY.

GOLF TEE.

Application filed March 31, 1928. Serial No. 266,162.

This invention relates to improvements in golf tees and is concerned more particularly with an improved form of golf tee which may be quickly and easily manufactured in 5 large quantities at low cost and which has for its principal object the provision of means whereby the height at which the golf ball is teed, or supported, above the ground is adjustable.

10 Another object of the invention is to provide a reusable golf tee of such design that it may be readily inserted in the ground to support a golf ball and which will offer a substantial resistance to withdrawal from 15 the ground if struck by a golf club and which may be easily withdrawn from the ground by the player after the ball has been driven from the tee.

20 A further object of the invention is to provide a reusable golf tee of such form that if it be struck with the face of a wooden club it will not cause injury to the club.

25 Another object is to provide a golf tee of telescopic form whereby a large number of tees may be telescoped one within the other to facilitate the carrying of the same in a compact arrangement.

30 A further object is so to color the tee as to make it readily distinguishable from the driving tee or area and from the fairway so that it may be readily located and recovered if displaced from the driving position by the player in making a drive.

35 A still further object of the invention is to provide a reusable golf tee of such form that it affords a relatively large, visible, surface area readily adapted to be used as advertising space.

40 The tee embodying the present invention is formed from a blank of sheet material, preferably of metal, such as, for example, aluminum, zinc, tin or iron, which blank may be formed into the tee by one operation of a punch press. The tee comprises a head 45 or ball-supporting section conforming to the surface of a golf ball and formed integral with a shank or body portion which is adapted to be inserted in the ground by the player. The body portion may assume any 50 desirable cross-sectional form but I prefer to make it non-homaloidal and to position the ball-supporting portion in alignment with the area defined by the body portion.

55 The height at which the ball is teed is varied by the depth of insertion of the body portion in the ground and to limit this depth to

predetermined amounts I provide a plurality of flaps or tongues associated with the body portion which may be depressed to project 60 from the surface of the body portion.

For a better understanding of the invention, reference may be had to the following description and the accompanying drawings, in which

Fig. 1 is a perspective view of a preferred 65 embodiment of the present invention;

Fig. 2 is a vertical cross-sectional view showing the tee inserted in the ground and supporting a golf ball;

Fig. 3 is a front elevation of the tee 70 viewed in the direction of the flight of the golf ball and showing the height-adjusting flaps or tongues lying flush with the body portion of the tee;

Fig. 4 is a cross sectional view of the tee 75 taken along the line 4-4 of Fig. 3 and showing one of the flaps or tongues projecting outwardly from the body portion of the tee, and

Fig. 5 is a plan view of the blank of sheet 80 material from which the tee is made, showing the flaps or tongues cut in the body portion of the tee.

In the drawing, the numeral 1 indicates 85 the shank or body portion of a golf tee embodying the present invention and the numeral 2 indicates the head or ball-supporting portion upon which a golf ball 3 is adapted to be placed and held in position as illustrated.

The tee may be made of any suitable 90 metallic or non-metallic sheet material, although I prefer to make it of aluminum which has been previously made into a blank

4 having substantially the form shown in Fig. 5. The body portion of the tee is 95 formed by bending the material of the blank 4 into a non-homaloidal form, preferably cylindrical as illustrated more clearly in Fig.

4. It will be appreciated, of course, that the body portion of the tee may assume any 100 one of a large variety of shapes, but I have found it desirable to make it of such shape, that the vertical edges of the shank are located a substantial distance apart to permit the easy insertion and withdrawal of 105 the tee into and from the ground and in order that a large number of the tees may be telescoped one within the other to facilitate the carrying of the same in a compact arrangement.

110 As shown in the drawing the open side of the tee faces in the direction of the line

of flight of the golf ball as it leaves the tee. There is no danger therefore that the golf club will strike the edges of the body portion of the tee and so be damaged thereby. By making the surface of the tee, adjacent the side of the ball which is struck, cylindrical there is no danger of injury to the face of the golf club should it strike the tee when the player makes a drive.

10 The head or ball supporting portion 2 of the tee is formed from the material of the blank 4 by bending the end 5 of the blank over to lie in alignment with the area defined by the body portion 1 and to form a

15 concave upward surface conforming to the exterior of a golf ball as shown in the drawing. The end 5 of the blank is preferably rounded as shown in Fig. 5 so that when it is bent over to form the head 2 of the tee,

20 the head so formed will be substantially spherical thus providing uniform contact with the golf ball throughout the area of the tee head. As it may be observed from the drawing, the head 2 of the tee is made

25 integral with substantially the entire upper periphery of the body portion 1 so that a strong, durable tee is formed which may be inserted into or withdrawn from the ground by the application of pressure on the upper 30 or lower surfaces respectively, of the head. To facilitate the bending of the blank 4 to form the ball-supporting portion, I prefer to cut away the material of the blank adjacent the end 5 as indicated at 6 in Fig. 5.

35 From the above description, it will be apparent to those skilled in the art that the tee may be completely formed from the material of the blank by a single operation of a punch press thus rendering possible the 40 production of a large number of the tees at a small cost.

The tee may be conveniently inserted in the ground by placing the golf ball 3 in contact with the head 2 of the tee and inserting the index finger between the edges of the shank 1 and against the under side of the head 2 and applying sufficient pressure by means of the thumb on the top of the golf ball. To provide sufficient surface 45 to support the ball and to furnish a suitable bearing surface for the index finger, the edges of the shank 1 are positioned a substantial distance apart and the head 2 extends slightly beyond the area defined by 50 the shank. The head also forms a convenient means for withdrawing the tee from the ground by inserting the index finger under the head and applying an upward pull. Because of the cylindrical form of the shank 55 1 and the fact that it is made of sheet material the tee may be readily inserted in the ground, but because of its relatively large lateral extension, it offers considerable resistance to withdrawal when struck by a 60 golf club and would ordinarily be displaced

but a short distance from its driving position if so struck by a club. The lower end of the tee may be, and preferably is, made convergent as indicated at 7 to facilitate the insertion of the tee in the ground.

70 After a player has determined at which height above the ground he prefers to tee the ball, it is desirable that the tee be provided with means which will enable him to tee the ball at this height conveniently and rapidly.

75 To accomplish this result I provide the shank or body portion 1 of the tee with a series of flaps or tongues 8 formed integral with the tee at various heights as shown.

80 Although only two tongues are illustrated in the drawing it is obvious that a larger number may be provided to furnish greater variation in regulating the height at which the ball may be teed.

85 These tongues are preferably formed by cutting upright, substantially U-shaped slits in the blank 4 or they may be cut when the tee is being formed from the blank. I have found it more convenient to permit the tongues 8 to

90 remain flush with the surface of the shank 1 until the player has determined which one should be used to limit the insertion of the tee in the ground to the desired distance.

95 The player may thereafter, in inserting a tee in the ground, depress the desired tongue so that it projects substantially perpendicular to the surface of the shank 1 on either side thereof, although preferably interiorly of the shank, and push the tee into the

99 ground until the depressed tongue contacts 100 with the surface of the ground. After the drive has been made and the tee withdrawn from the ground, the tongue may be bent back to lie flush with the surface of the shank or body portion 1 so that the several

105 tees carried by the player may be telescoped one within the other for convenience in carrying them in a compact arrangement.

It sometimes happens that a player in 110 making a drive strikes the tee with the head of his club with such force that the tee is pulled from the ground and it may be driven from the driving tee or area into the fairway.

115 If the color of the tee be such that it is not readily distinguishable from the driving tee or area and from the fairway it becomes difficult to locate the tee. Therefore, to 120 overcome this difficulty I make the tee of a color readily distinguishable from the driving tee or area and from the fairway. The

125 particular color employed will of course be determined finally by the color of the driving tees and fairways in the terrain in which it is to be used but I have found that orange colored tees are sufficiently discernible in

most instances to assist the player in locating the tee when it has been driven from its driving position. The color may be applied to the tee by a coating of enamel or paint or

130 it may be applied in any other suitable way.

The relatively large surface area of the tee affords a convenient space for advertising matter which may be stamped into the material of the tee when it is being formed or which may be printed or otherwise associated with the tee at a later time.

Having thus described this form of my invention, I wish it to be understood that various changes may be made by those skilled in the art without departing from the spirit and scope of my invention.

What I claim and desire to protect by Letters Patent is:

1. A tee for supporting a golf ball comprising, a body portion adapted to be inserted in the ground, a ball-supporting portion connected therewith and means for limiting the depth of insertion of said body portion, said means normally lying flush with the surface of said body portion but adapted to be depressed therefrom.

2. A tee for supporting a golf ball comprising, a body portion adapted to be inserted in the ground, a ball-supporting portion connected therewith and a plurality of positive means associated with said body portion at various heights for limiting the insertion of the same to one of several selectable depths, said means normally lying flush with the surface of said body portion but adapted to be depressed therefrom.

3. A tee for supporting a golf ball comprising, a body portion adapted to be inserted in the ground, a ball-supporting portion connected therewith and a plurality of tongues or flaps formed integral with said body portion at various heights and adapted to be depressed so as to project therefrom to limit the depth of insertion of said body portion to one of several selectable depths.

4. A tee for supporting a golf ball comprising, a body portion of non-homaloidal sheet material adapted to be inserted in the ground, a ball-supporting portion connected therewith and a plurality of positive means associated with said body portion at various heights for limiting the insertion of the same to one of several selectable depths, said means normally lying flush with the surface of said body portion but adapted to be depressed therefrom.

5. A tee for supporting a golf ball comprising, a cylindrical body portion of sheet material adapted to be inserted in the ground, a ball-supporting portion connected therewith and a plurality of positive means associated with said body portion at various heights for limiting the insertion of the same to one of several selectable depths, said means normally lying flush with the surface of said body portion but adapted to be depressed therefrom.

6. A tee for supporting a golf ball comprising, a body portion of non-homaloidal sheet material whose edges are a substantial

distance apart, said body portion being adapted to be inserted in the ground, a ball-supporting portion in alignment with the area defined by said body portion and formed integral therewith throughout its upper periphery and means for limiting the depth of insertion of said body portion, said means normally lying flush with the surface of said body portion but adapted to be depressed therefrom.

7. A tee for supporting a golf ball comprising, a body portion of non-homaloidal sheet material whose edges are a substantial distance apart, said body portion being adapted to be inserted in the ground, a ball-supporting portion in alignment with the area defined by said body portion and formed integral therewith throughout its upper periphery and a plurality of positive means associated with said body portion at various heights for limiting the insertion of the same to one of several selectable depths, said means normally lying flush with the surface of said body portion but adapted to be depressed therefrom.

8. A tee for supporting a golf ball comprising, a body portion of non-homaloidal sheet material whose edges are a substantial distance apart, said body portion being adapted to be inserted in the ground, a ball-supporting portion in alignment with the area defined by said body portion and formed integral therewith throughout its upper periphery and a plurality of tongues or flaps formed integral with said body portion at various heights and adapted to be depressed so as to project therefrom to limit the depth of insertion of said body portion to one of several selectable depths.

9. A tee for supporting a golf ball comprising, a body portion of non-homaloidal sheet material whose edges are a substantial distance apart, said body portion being adapted to be inserted in the ground, a ball-supporting portion in alignment with the area defined by said body portion and formed integral therewith throughout its upper periphery and a plurality of positive means associated with said body portion at various heights for limiting the insertion of the same to one of several selectable depths, said means normally lying flush with the surface of said body portion, but adapted to be depressed therefrom, the lower end of said body portion being convergent to facilitate the insertion thereof in the ground.

10. A golf ball tee formed from a blank of sheet material and comprising, a non-homaloidal body portion whose edges are a substantial distance apart, an upwardly concave portion conforming to the surface of the ball and in alignment with the area defined by said body portion and formed from the entire upper periphery of the body portion and a plurality of tongues formed in the side of

said body portion and adapted to be depressed therefrom.

11. A golf ball tee of a color readily discernible in the terrain in which it is to be used and formed from a blank of sheet material and comprising, a non-homaloidal body portion whose edges are a substantial distance apart, an upwardly concave portion conforming to the surface of the ball and in

alignment with the area defined by said body portion and formed from the entire upper periphery of the body portion and a plurality of tongues formed at various heights in the side of said body portion and adapted to be depressed therefrom, the lower end of said body portion being convergent.

WILLIAM JAMES BARNES.
